EX

DESIGN.

J. B. BRILBECK.
BADGE.

No. 17,738.

Patented Sept. 27, 1887.

UNITED STATES PATENT OFFICE.

JOHN B. BRILBECK, OF SYRACUSE, NEW YORK.

DESIGN FOR A BADGE.

SPECIFICATION forming part of Design No. 17,738, dated September 27, 1887.

Application filed July 5, 1887. Serial No. 243,464. Term of patent 7 years.

To all whom it may concern:

Be it known that I, JOHN B. BRILBECK, a citizen of the United States, residing at Syracuse, in the county of Onondaga and State of New York, have invented and produced a new and original Design for Emblems or Badges, of which the following is a specification, reference being had to the accompanying drawing, forming part thereof.

10 The leading features of my design are, first, a star-shaped figure formed of a cross having rope-work edges; second, a center composed of a plain surface of circular form having periphery of rope-work; third, a bar from which the cross is pendent by links, said bar having edges in rope-work; fourth, a badge composed of a star, a center, and a bar, all ornamented upon their edges with rope-work; and, fifth, a badge composed of a cross set upon crossed 20 naked swords disposed points upward and the points projecting between the top and the two side parts of the cross and the handles between the bottom and the two side parts thereof.

In the accompanying illustration, A is the cross, of four parts, $b b b b$, subdivided, creating eight points, by the angles c . The edges of these body parts b are ornamented with rope-

work. A rope-work circle constitutes the center, inclosing a plain surface. The body parts within the rope-work are also plain. The cross and center are set upon naked swords crossed at right-angles, points upward. The bar from which the cross is pendent is also edged with rope-work in rectangular outline and has a central top ornament composed of a crown. 35 The bar, cross-body parts b , and circular center are provided with letters, signs, or symbols to designate any particular society, lodge, or organization.

I claim—

40 A design for a badge having an eight-pointed star-shaped figure with rope edges, a rope-circle center, plain surfaces within the rope-work, and naked swords crossed points upward and pendent from a bar bordered with rope-work 45 and surmounted by a crown, as shown and described.

In witness whereof I have hereunto set my hand this 1st day of July, 1887.

JOHN B. BRILBECK.

In presence of—

W.M. C. RAYMOND,
W.M. BOON.
